(57) **CLAIM**

The ornamental design for a stool with removable table top, as shown and described.

DESCRIPTION

FIG. 1 is a front, left, top perspective view of a stool with removable table top, showing my new design;

FIG. 2 is a rear, right, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, left, top perspective view of the stool with removable table top, showing the stool separately for ease of illustration;

FIG. 10 is a rear, right, bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a rear, right, bottom view thereof;

FIG. 17 is a front, left, top perspective view of the stool with removable table top, showing the table top separately for ease of illustration;

FIG. 18 is a rear, right, bottom perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof; and,

FIG. 25 is a front, left, top exploded perspective view of FIG. 1.

The broken lines in the drawings illustrate the portions of the stool with removable table top, which form no part of the claimed design.
